9 Claims. (Cl. 261—41)

This invention relates to means for supplying air-fuel mixture to engines, and more particularly to carburetors for use on internal combustion engines of automotive vehicles.

Prior carburetors used on present engines in some instances have a tendency to supply too rich a mixture of air and fuel as the engine speed increases from idling speed at part-open throttle and to supply too lean a mixture when the engine speed has increased beyond a certain value at part throttle. This tendency is particularly critical in cases where the carburetor is one that is adapted quickly to reach the transfer point where the high speed circuit of the carburetor takes over from the low speed circuit of the carburetor as the engine speed increases from idling speed upon wide-open throttle. The principal object of this invention is to provide for leaning out the mixture when coming up from idle speed at part throttle to avoid having too rich a mixture during the initial stage of speed increase, and to enrich the mixture during the final stage of speed increase at part throttle to avoid having too lean a mixture during the latter stage. This object is attained, according to the present invention, by providing a convertible bleeder and fuel nozzle between the high speed fuel passage and the mixture conduit of the carburetor located within the influence of air flow through the mixture conduit and so directed in relation to the direction of air flow that the air pressure on the conduit side of the bleed decreases with increase of air velocity in such manner that, at relatively low engine speeds and corresponding relatively low air velocities, air bleeds from the conduit into the fuel passage, with the result that the mixture is leaned out, and, at relatively high engine speeds and corresponding relatively high air velocities, the bleeder converts to a fuel nozzle and discharges fuel from the fuel passage into the mixture conduit, with the result that the supplementary nozzle action of the bleeder causes the mixture to be enriched. Other objects and features will be in part apparent and in part pointed out hereinafter.

The invention accordingly comprises the constructions hereinafter described, the scope of the invention being indicated in the following claims.

In the accompanying drawings, in which one of various possible embodiments of the invention is illustrated,

Fig. 1 is a plan view of a four-barrel carburetor in which the invention is incorporated;

Fig. 2 is a vertical section taken on line 2—2 of Fig. 1;

Fig. 3 is a vertical section taken on line 3—3 of Fig. 1;

Figs. 4 and 5 are vertical sections taken on lines 4—4 and 5—5, respectively, of Fig. 1, on a reduced scale as related to Fig. 1;

Fig. 6 is a horizontal half-section taken on line 6—6 of Fig. 3, appearing as if the cover for the carburetor were removed;

Fig. 7 is an enlarged plan view per se of a special nozzle used in the carburetor for incorporating the invention therein, being viewed on line 7—7 of Fig. 2, and with parts broken away and shown in section;

Figs. 8 and 9 are vertical sections taken on lines 8—8 and 9—9, respectively, of Fig. 7;

Fig. 10 is a bottom plan view of Fig. 7; and,

Fig. 11 (Sheet 3) is a chart illustrating certain mixture ratio/engine speed characteristic curves.

Corresponding reference characters indicate corresponding parts throughout the several views of the drawings.

Referring to the drawings, the invention is illustrated

10 in its application to a multi-barrel multi-stage carburetor of the type commonly referred to as a four-barrel carburetor. As shown, the carburetor comprises a main body casting 1 which is formed to provide a throttle body section 3 and a float bowl section 5 on the throttle body section. The throttle body section 3 has lugs 7 for attachment to the intake manifold of the engine on which the carburetor is used. The float bowl section is generally of rectangular shape in plan, its side walls being designated 9 and 11 and its end walls being designated 13 and 15. Partitions 17 and 19 extend between the side walls 9 and 11 adjacent the end walls 13 and 15 to define two float bowls 21 and 23, one at each end of the fuel bowl section 5. Each of the partitions 17 and 19 has a central inwardly directed offset 25 providing a 20 vertically extending recess such as indicated at 27. A partition 29 extends between offsets 25 dividing the space bounded by side walls 9 and 11 and partitions 17 and 19 into a primary section 31 and a secondary section 33. The primary section is formed to provide two side-by-side 25 primary mixture conduits or barrels 35 and 37, and the secondary section is formed to provide two side-by-side secondary mixture conduits or barrels 39 and 41. Each primary barrel is formed as a venturi. Secured to the top of the fuel bowl section is a float bowl cover 43 30 formed to provide a circular air horn 45. The horn has a diametrical partition 47 coplanar with partition 29 dividing it into a primary air inlet 31a above section 31 and a secondary air inlet 33a above section 33.

The cover 43 has a fuel inlet 49 and an inlet passage 51 40 connecting the inlet to the two float bowls 21 and 23. Entry of fuel to the bowls from passage 51 is controlled by two float valves 53, one for each bowl (see Fig. 4). Each of these valves is controlled by a float 55 in the respective bowl. The valves and floats may be of any 45 suitable construction, their details not being critical so far as this invention is concerned. The bowl 21 supplies the barrel 35 and the bowl 23 supplies the barrel 37 via identical systems. Only the system for barrel 35 will be described, and it will be understood that the system for barrel 37 is identical.

Barrel 35 has an upwardly facing shoulder 57 at the side thereof toward the respective float bowl 21 (see Figs. 2 and 3). Extending down from this shoulder is a vertical well 59. The casting 1 is formed with a passage 61 from the bottom of recess 27 of bowl 21 to the bottom of the well 59. This passage is formed by drilling a vertical hole 63 extending down from the bottom of recess 27 to an intersection with an inclined hole 65 drilled from the bottom of throttle body section 3 to the lower end of the well. The outer end of hole 65 is plugged as indicated at 67. Threaded in the upper end of hole 63 is a metering jet 69. A metering rod 71 extends down in recess 27 and through the jet from a vacuum-responsive control contained in the float bowl section 5 under a cap 73. The metering rod and control are of known construction and need not be further described, details thereof not being critical so far as this invention is concerned. It will be understood that the control for the rod acts to move the metering rod up and down in response to change in intake manifold vacuum, for high speed fuel metering.

Shoulder 57 serves to support a nozzle body 75 (see

Figs. 2, 3 and 5-10) at the upper end of the primary barrel. This body comprises a casting formed to provide a head 77, and arm 79 extending horizontally from the head, and a boost venturi 81 at the outer end of the arm. The head is secured on the shoulder 57 as by screws 83. A hole 85 is drilled through the head 77 and the arm 79 from the outside of the head to open into the boost venturi 81. The outer end of this hole is closed as by a welch plug 87. The hole 85 is angled upward from the outside of the head to the boost venturi 81. A hole 89 is drilled up from the bottom of the head to an intersection with angled hole 85. A hole 91 of smaller diameter than hole 89 is drilled to extend up from angled hole 85 coaxial with the hole 89, and to an intersection with a horizontally extending hole 93 drilled in head 77 adjacent its upper end (see Fig. 9).

A fuel tube 95 has its upper end pressed in hole 89 and extends down into the well 59. An idle fuel tube 97 of smaller diameter than tube 95 has its upper end pressed into hole 91 and extends down within the tube 95. Idle tube 97 has a restricted lower end 99 which extends down below the lower end of tube 95. A nozzle tube 101 is pressed in the angled hole 85, extending from hole 89 through the arm 79 into the venturi 81. In accordance with this invention, nozzle arm 79 is formed with a downwardly extending tubular projection 103, the passage in which is designated 105. Nozzle tube 101 has an annular peripheral groove 107 registering with passage 105 and a hole 109 in the bottom of the groove registering with passage 105. Hole 109 is of smaller diameter than the inside diameter of nozzle tube 101 and of smaller diameter than passage 105. The space 111 between tubes 95 and 97 and the nozzle tube 101 provides a high speed fuel passage from the well 59 to boost venturi 81. Hole 109 and passage 105 provide a restricted bleeder for this high speed fuel passage 111, 101 within the influence of the primary barrel 35 (the main venturi) where the action of the bleeder is subject to air flow through the carburetor, as will be made clear.

Idle tube 97 is part of a low speed circuit for delivering fuel at low speed operation to idle port 113 (see Fig. 5) in the primary barrel. This low speed circuit includes holes 91 and 93 in the nozzle head 77. Head 77 has a vertical hole 115 (see Fig. 9) extending up from its bottom with a restricted air bleed hole 117 through the upper end of the head. Hole 93 has a restricted economizer passage 119 extending from its inner end into the vertical hole 115. An air metering plug 121 is pressed in the outer end of hole 93. Air is by-passed from the air horn 45 through and metered by plug 121 into the hole or passage 93. Air bleeds into the vertical hole 115 from the air horn through bleed hole 117 to lean the mixture delivered through the economizer 119. The vertical hole 115 is aligned with a hole extending down from shoulder 57 which constitutes part of a passage 123 for flow of fuel-air mixture from hole 115 to the idle port 113, the flow being adjustable by means of the usual idle adjusting screw 125.

Head 77 has a second vertical hole 127 (see Fig. 8) in the upper end of which is pressed a nozzle bleed tube 129 having a restricted upper end 131. The bottom of the head is formed with a slot 133 connecting the lower end of the vertical hole 127 and the hole 89 for communication between the hole 127 and the well 59. Fuel tube 95 has a hole 135 adjacent its upper end directed toward the slot 133. This allows air to bleed into the space 111 between tubes 95 and 97.

Each of the primary barrels 35 and 37 has the usual primary throttle valve 137 (see Figs. 2 and 5) at its lower end, the two primary throttle valves being fixed on the usual primary throttle shaft 139 journaled in the throttle body section 3. In the primary air inlet portion 31a of the air horn 45 is the usual choke valve 141, the usual choke control being indicated at 143 in Fig. 1. The carburetor has the usual accelerator pump such as indi-

cated at 145 in Fig. 4 for supplying fuel to the primary barrels in response to opening of the primary throttles via a pump discharge jet cluster indicated at 147 in Figs. 1, 2 and 6. Vents such as indicated at 149 are provided for venting the float bowls to the interior of the air horn 45, and vent holes such as indicated at 151 are provided for venting the float bowls to the outside.

At the upper end of each secondary barrel 39 and 41 is a venturi cluster 153 having a fuel nozzle 155 supplied with fuel from the respective float bowl via a passage part of which is indicated at 157 in Fig. 5. Each secondary barrel has the usual secondary throttle valve 159 at its lower end, the two secondary throttle valves being fixed on the usual secondary throttle shaft 161 journaled in the throttle body section 3. Each secondary barrel also has the usual velocity valve 163 therein, the two velocity valves being fixed on shaft 165 which carries weights such as indicated at 167 for biasing the velocity valves closed.

At the ends of the carburetor, as shown in Fig. 1, are the usual mechanisms for controlling the primary throttle shaft 139 and the secondary throttle shaft 161. It will be understood that these mechanisms include such components as the usual actuating lever 169 fixed on one end of the primary throttle shaft 139 adapted for connection of an actuating rod for actuating the primary throttle shaft from the usual pedal, the usual fast-idle cam 171 connected as indicated at 173 to the choke valve shaft 175, and the usual mechanism such as indicated at 177 for operating the secondary throttle shaft 161 to open the secondary throttle valves 159 on opening of the primary throttle valves a predetermined amount. Details of these mechanisms are not critical insofar as this invention is concerned, and further detailed description thereof is therefore omitted.

Operation is as follows:

Assuming that the engine is idling, and that the primary throttle valves 137 are partly opened to come up off idling, fuel is supplied to each of the primary barrels 35 and 37 via the high speed circuit for each of these barrels including space 111 between tubes 95 and 97 and the nozzle tube 101 when the engine speed increases to the point where the velocity of air flowing through the barrels is sufficient for the high speed circuit to take over from the low speed circuit. At this point, the air velocity is still relatively low, and the pressure at the mouth of bleeder projection 103 (which is directed downstream relative to the direction of air flow) is accordingly relatively high with the result that air from the primary barrel (the main venturi or mixture conduit) bleeds through projection 103 and the bleeder hole 109 into the nozzle tube 101 to lean the mixture of air and fuel supplied to the engine. After the high speed circuit has taken over and upon further increase in engine speed with resultant increase in the velocity of air flowing through each primary barrel, the pressure at the mouth of bleeder projection 103 decreases, and the bleeding of air into the nozzle tube 101 through bleeder hole 109 decreases. Eventually, a state of balance is reached where bleeding of air through hole 109 into the nozzle tube 101 ceases. Then, upon further increase in engine speed with resultant further increase in the velocity of air flowing through each primary barrel and further decrease in the pressure at the mouth of bleeder projection 103, fuel is discharged from nozzle tube 101 through bleeder hole 109 and projection 103 into the primary barrel to enrich the mixture of air and fuel supplied to the engine. As the engine speed and air velocity continue to increase, and the pressure continues to decrease, fuel is discharged through hole 109 at an increased rate.

The solid line curve A in Fig. 11 is the part-throttle mixture ratio/engine speed characteristic curve of the above described carburetor having bleeder 109, 103. Curve W is the wide-open throttle mixture ratio/engine speed characteristic curve. The horizontal coordinates in

Fig. 11 represent engine speed in revolutions per minute. The vertical coordinates represent mixture ratio in terms of pounds of air to pounds of fuel. As appears from curve A the mixture ratio increases (the mixture becomes leaner) as engine speed increases in coming up from idling at part throttle until the speed reaches about 1800 r.p.m., at which point the mixture is the so-called economy mixture, then levels off and remains substantially constant until engine speed increases to about 2600 r.p.m. At this point, as will be understood, the metering rods 71 are actuated to enrich the mixture to obtain the so-called power mixture (about 12 to 1 ratio). This power mixture ratio is fully attained at about 3000 r.p.m., as shown, and is maintained substantially constant with further increase in speed. It will be observed that the mixture ratio comes down relatively sharply at part throttle to the economy mixture, this being due to the action of bleeder 109, 103 to lean the mixture when the high speed circuit comes into operation in coming off idle. The power mixture ratio is maintained substantially constant with increase in speed from 3000 r.p.m. due to the action of the bleeder 109, 103 to enrich the mixture at the higher engine speeds (and higher air velocities).

In contrast, Fig. 11 shows dotted line curve B representing the part-throttle mixture ratio/engine speed characteristic curve of the carburetor as it would be without any bleed. It will be observed that this curve starts flattening out at about 1200 r.p.m. and lies above curve A from about 1200 r.p.m. to about 2000 r.p.m., illustrating that the mixture is too rich in this region. Then, this curve droops down below curve A, comes up to the power mixture ratio beyond curve A, and droops off again, illustrating that the mixture is too lean at higher speeds. Dot-dash line curve C represents what would be the part-throttle mixture ratio/engine speed characteristic curve for a carburetor with a bleeder that functioned only to lean the mixture in coming off idle, but incapable of functioning to enrich the mixture at higher speeds by bleeding in fuel at higher speeds. It will be observed that this sags off at higher speeds like curve B.

In view of the above, it will be seen that the several objects of the invention are achieved and other advantageous results attained.

As various changes could be made in the above constructions without departing from the scope of the invention, it is intended that all matter contained in the above description or shown in the accompanying drawings shall be interpreted as illustrative and not in a limiting sense.

I claim:

1. A carburetor having a main venturi, a nozzle for flow of fuel from a source thereof into the main venturi, said nozzle having a boost venturi at the end thereof in the main venturi, and said nozzle having a bleeder located outward of the boost venturi and within the main venturi, said bleeder being directed downstream relative to the direction of air flow through the main venturi and thereby adapted to act in response to velocity of air flowing through the main venturi to bleed air from the main venturi into the nozzle at relatively low air velocities and to admit fuel from the nozzle into the main venturi at higher air velocities.

2. A carburetor having a main venturi, a nozzle body comprising an arm extending into the main venturi and a boost venturi at the end of the arm, said nozzle body having a fuel passage extending through said arm to said boost venturi, said fuel passage being in communication with a source of fuel, and said arm having a bleeder directed downstream relative to the direction of air flow through the main venturi and thereby adapted to act in response to velocity of air flowing through the main venturi to bleed air from the main venturi into said passage at relatively low air velocities and to admit fuel from the passage into the main venturi at higher air velocities.

3. A carburetor having a main venturi, said main

venturi having an upwardly facing shoulder at one side thereof, a nozzle body comprising a head secured on said shoulder, an arm extending from the head into the main venturi, and a boost venturi at the end of the arm, said nozzle body having a fuel passage extending from said head through said arm to said boost venturi, said fuel passage being in communication with a source of fuel, and said arm having a downwardly directed bleeder adapted to act in response to velocity of air flowing through the main venturi to bleed air from the main venturi into said passage at relatively low air velocities and to admit fuel from said passage into the main venturi at higher air velocities.

4. A carburetor having a float bowl section formed to provide a float bowl and a main venturi, with an upwardly facing shoulder at one side of said main venturi, a nozzle body comprising a head secured on said shoulder, an arm extending from the head into the main venturi and a boost venturi at the end of the arm, said nozzle body having a passage extending from the head through said arm to said boost venturi, said float bowl section having a well extending down from said shoulder, a fuel tube extending down from said head into said well, said tube opening at its upper end to said passage, said float bowl section being passaged for flow of fuel from the float bowl to said well, a nozzle tube in said passage extending into said boost venturi, said arm having a downwardly extending tubular projection, and said nozzle tube having a hole therein smaller than the internal diameter of the nozzle tube in communication with said tubular projection.

5. A carburetor having a float bowl section formed to provide a float bowl and a main venturi, with an upwardly facing shoulder at one side of said main venturi, a nozzle body comprising a head secured on said shoulder, an arm extending from the head onto the main venturi and a boost venturi at the end of the arm, said nozzle body having a passage extending from the head through said arm to said boost venturi, said float bowl section having a well extending down from said shoulder, a fuel tube extending down from said head into said well, said tube opening at its upper end to said passage, said float bowl section being passaged for flow of fuel from the float bowl to said well, a nozzle tube in said passage extending into said boost venturi, said arm having a downwardly extending tubular projection, and said nozzle tube having an annular peripheral groove registering with said projection and a hole in the bottom of the groove smaller than the internal diameter of the nozzle tube.

6. A carburetor having a float bowl section formed to provide a float bowl and a main venturi, with an upwardly facing shoulder at one side of said main venturi, a nozzle body comprising a head secured on said shoulder, an arm extending from the head into the main venturi and a boost venturi at the end of the arm, said nozzle body having a passage extending from the head through said arm to said boost venturi, said float bowl section having a well extending down from said shoulder, a fuel tube extending down from said head into said well, said tube opening at its upper end to said passage, said float bowl section being passaged for flow of fuel from the float bowl to said well, a nozzle tube in said passage extending into said boost venturi, said arm having a downwardly extending tubular projection, said nozzle tube having a hole therein smaller than the internal diameter of the nozzle tube in communication with said tubular projection, an air bleed passage extending through said head to said well, and said fuel tube having a hole therein adjacent its upper end for bleeding air from said air bleed passage into said fuel tube.

7. A progressive feeding type of carburetor having a body, a mixture conduit extending through said body,

venturi means in said mixture conduit, a main fuel nozzle opening into said venturi means in a zone of comparatively high pressure drop in the free stream air flow through said mixture conduit, a source of fuel, a fuel passage connecting said source of fuel with said fuel nozzle, and a convertible bleeder and fuel nozzle connected with said fuel passage between said fuel nozzle and said source of fuel; said convertible bleeder and fuel nozzle having an outlet located in said mixture conduit in a zone wherein the pressure drop in the free stream air flow through the mixture conduit is less than in said first zone during initial operation of said main fuel nozzle so as to bleed air into said fuel passage, said outlet for said convertible bleeder and fuel nozzle being directed with respect to said mixture conduit to be aspirated by the air stream in said mixture conduit, whereby at high air stream velocity through said mixture conduit the flow in said convertible bleeder reverses and fuel is discharged simultaneously from said fuel passage by said bleeder and by said main fuel nozzle.

8. A progressive feeding type of carburetor having a body, a mixture conduit extending through said body, venturi means in said mixture conduit, a main fuel nozzle opening into said venturi means in a zone of comparatively high pressure drop in the free stream air flow through said mixture conduit, a source of fuel, a fuel passage connecting said source of fuel with said fuel nozzle, and a convertible bleeder and fuel nozzle; said convertible bleeder and fuel nozzle having a connection with said main fuel nozzle and an outlet located in said mixture conduit in a zone wherein the pressure drop in the free stream air flow through the mixture conduit is less than in said first zone during initial operation of said main fuel nozzle so as to bleed air into said main fuel nozzle, said outlet for said convertible bleeder and fuel nozzle being directed with respect to said mixture conduit to be aspirated by the air stream through said venturi means, whereby as air stream velocities through said venturi means increase the air bleeding action of

said convertible bleeder progressively decreases to zero and then reverses to discharge fuel simultaneously from said convertible bleeder and fuel nozzle and from said main nozzle.

- 5 9. A progressive feeding type of carburetor having a body, a mixture conduit extending through said body, venturi means in said mixture conduit, a main fuel nozzle opening into said venturi means in a zone of comparatively high pressure drop in the free stream air flow through said mixture conduit, a source of fuel, a fuel nozzle, a fuel passage connecting said source of fuel with said fuel nozzle, and a convertible bleeder and fuel nozzle connected with that fuel passage between said fuel nozzle and said source of fuel; said convertible bleeder and fuel nozzle having an outlet located in said mixture conduit in a zone wherein the pressure drop in the free stream air flow through the mixture conduit is less than in said first zone during initial operation of said main fuel nozzle so as to bleed air into said fuel passage, but increases with increased air flow through said mixture conduit, said outlet for said convertible bleeder and fuel nozzle being directed with respect to said mixture conduit to be aspirated by the air stream in said conduit, whereby the flow in said convertible bleeder and fuel nozzle progressively decreases with increased air flow velocities through said mixture conduit to reduce the delivery from said main fuel nozzle during initial operation thereof in a retrogressive manner and subsequently reverses to act as a supplementary fuel nozzle at still higher air inflow velocities through said mixture conduit.
